UNITED STATES PATENT OFFICE.

OLOFF N. SANDERS, OF LAGRANGE, ILLINOIS.

CLOTHES-LINE REEL.

SPECIFICATION forming part of Letters Patent No. 687,942, dated December 3, 1901.

Application filed December 20, 1900. Serial No. 40,555. (No model.)

To all whom it may concern:

Be it known that I, OLOFF N. SANDERS, a citizen of the United States, residing at La-
grange, in the county of Cook and State of
Illinois, have invented new and useful Im-
provements in Clothes-Line Reels, of which
the following is a specification.

This invention relates to new and useful im-
provements in clothes-line reels; and its pri-
10 mary object is to provide a device of simple
construction which is light and durable and
which is provided with means whereby the
line may be unwound at a desired speed.

A further object is to provide means of
15 peculiar construction whereby the reel may
be turned for the purpose of untwisting the
rope without necessitating the release of the
handle.

With these and other objects in view the
20 invention consists in providing a yoke, be-
tween the ends of which is mounted a reel
formed, preferably, of wire wheels arranged
at opposite ends of a shaft. A crank is ar-
ranged at one end of the shaft and is pro-
25 vided with a suitable handle, whereby the
shaft may be revolved. Spring-yokes extend
from the yoke of the shaft and are provided
with inwardly-extending loops which are
adapted to interlock and which can be so ar-
30 ranged as to clamp the rope passing there-
between, if desired, thereby retarding its mo-
tion.

The invention also consists in providing a
hand which is loosely mounted upon a bolt
35 extending from the center of the yoke of the
reel, and a thumb-nut is mounted upon the
outer end of this bolt and is adapted when
turned inward to clamp upon the handle and
hold the same fixed upon said bolt. A wire
40 or rod is loosely connected to one of the ears
of the thumb-nut and is adapted to swing
into a longitudinally-extending slot formed
within the end of the bolt, and this rod serves
the purpose of a crank when it is desired to re-
45 move the yoke without releasing the handle.

The invention also consists in certain novel
features of construction and combination of
parts, which will be hereinafter fully de-
50 scribed and claimed, and illustrated in the
accompanying drawings, showing the pre-
ferred form of my invention, and in which—

Figure 1 is a side elevation of the reel, the

position of the clothes-line thereon being
shown in dotted lines. Fig. 2 is a top plan
view. Fig. 3 is a section on the line xx of
Fig. 2. Fig. 4 is a detail view of the yoke, show-
ing its loops and bolt. Fig. 5 is an end view
of the yoke.

Referring to the drawings by numerals of
reference, 1 is a yoke, within the ends of which
is journaled a shaft 2, having a crank 3 at one
end, said crank being provided with a han-
dle 4, whereby the same may be readily
grasped and turned. Wheels 5 are secured
to the shaft 2 at points adjacent to the ends
thereof, and these wheels are of the same size
and are preferably formed of wire. A coil-
spring 6 surrounds the shaft 2 and bears at
one end against a collar on the yoke-shaft and
at the other end against the yoke, and this
spring serves to prevent the reel from unwind-
ing too rapidly when the rope is being drawn
therefrom. Strips 7 of spring metal, prefer-
ably wire, extend longitudinally from the
ends of the yoke, and these strips are bent
inward at the center to form loops 8 and 9,
respectively. One of these loops 8 overlaps
the intermediate portion of the remaining
loop 9, and the sides of the loop 8 are bent so
as to form recesses adapted to receive said in-
termediate portion of the loop 9. By this con-
struction the spring-strips 7 may be moved
from or toward each other and may be locked
in adjusted position. It is of course under-
stood that these strips are pivoted to the ends
of the yoke, so as to permit the same to be
swung from or toward each other.

A bolt 10 extends longitudinally from the
center of the yoke 1, and the free end thereof
is threaded, as at 11, and provided with a lon-
gitudinally-extending slot 12. A handle 13
is loosely mounted upon the bolt 10, and a
thumb-nut 14 engages the threaded end of
said bolt and is adapted when turned inward
to clamp the handle in position thereon. A
rod 15 is pivoted to one of the ends of the
thumb-nut and when swung inward will en-
gage the slot 12 of the bolt, and said rod can
then be used as a crank for turning the bolt
within the handle 13 after the thumb-nut has
been removed from contact with said handle.

One end of the clothes-line is adapted to be
secured to the reel, after which the line is
wound on the reel, and the remaining end is

then inserted between the loops 8 and 9. It will of course be understood that the clothes-line can be readily wound upon the reel by turning the same by means of the crank 3. 5 Should the line become twisted while the same is being wound, it is merely necessary to throw the rod 15 into engagement with the end of the bolt 10, and said rod can then be used as a crank for turning the bolt. As this bolt is 10 secured to the center of the yoke, it is obvious that the yoke will turn therewith, the bolt 10 revolving within the handle 13. After the line has been wound upon the reel the handle 13 is clamped upon its bolt 10 by releasing the rod 15 from engagement with said bolt and then turning the thumb-nut 14 inward until the same clamps upon the handle. If it is desired to unwind the line rapidly, the 15 loops 8 and 9 are pressed toward each other, so as to throw their intermediate portions farther apart. The line may then be drawn from the reel without having its movement retarded by said loops. The spring 6 upon the shaft 2, however, will prevent the reel from 20 revolving too rapidly. When it is desired to retard the movement of the clothes-line, the intermediate portions of the loops should be pressed toward each other until the rope is clamped therebetween. It will of course be 25 understood that the recesses formed in the loop 8 will receive the intermediate portion of the remaining loop 9, and thereby lock the loops in either of the positions to which they are moved.

30 By referring to the drawings it will be seen that the pivoted rod 15 is provided with a loop or eye 16 at its free end. This is provided so that the device can be readily suspended from a hook or nail when not in use.

35 In the foregoing description I have embodied the preferred form of my invention; but I do not wish to be understood as limiting myself thereto, as I am aware that modifications may be made therein without departing from the principle or sacrificing any of the advantages of this invention, and I there-

fore reserve to myself the right to make such changes as fairly fall within the scope thereof.

Having thus described the invention, what is claimed, and desired to be secured by Letters Patent, is—

1. The combination with a yoke; of a reel journaled therein, spring-metal strips pivoted to the yoke, inwardly-extending loops formed with said strips and adapted to overlap each other, one of said loops being provided with recesses for the reception of the intermediate portion of the remaining loop, and means for revolving the reel. 55

2. The combination with a yoke; of a reel journaled therebetween, pivoted strips extending from the ends of the yoke, spring-loops formed with said strips and extending toward each other and normally overlapping, one of said loops being provided with recesses 65 for the reception of the intermediate portion of the remaining loop, a crank for revolving the reel, and means contacting with the reel for retarding the movement thereof.

3. The combination with a yoke, of a reel 70 journaled therein, a bolt projecting from the yoke and slotted at its outer end, a handle loosely mounted on said bolt, a nut upon the bolt, and a rod pivotally secured to said nut, and adapted to be swung into the slot of the 75 bolt.

4. The combination with a yoke; of a shaft journaled therein, wheels secured to the shaft, a coil-spring mounted upon the shaft and adapted to retard the movement of the wheels, 80 spring-strips pivoted to the ends of the yoke, and loops extending inward from said strips and adapted to overlap, one of said loops being recessed to receive the intermediate portion of the remaining loop. 85

In testimony whereof I affix my signature in presence of two witnesses.

OLOFF N. SANDERS.
